UNITED STATES PATENT OFFICE.

DAVID LEONARD, OF ST. LOUIS, MICHIGAN.

TILE-MOLDING MACHINE.

No. 848,664.

Specification of Letters Patent.

Patented April 2, 1907.

Application filed May 18, 1906. Serial No. 317,437.

To all whom it may concern:

Be it known that I, DAVID LEONARD, a citizen of the United States, residing at St. Louis, in the county of Gratiot and State of Michigan, have invented a new and useful 5 Tile-Molding Machine, of which the following is a specification.

This invention relates to machines for molding tiles; and its object is to provide a 10 mold of novel construction in which the material of which the tile is to be formed can be firmly packed or tamped and from which the molded object can be easily removed without danger of injury thereto.

15 A still further object is to provide a machine which is simple in construction and which can be easily and quickly operated.

With the above and other objects in view the invention consists of a table in which is 20 mounted a slideable core adapted to be readily raised above or dropped below the top of the table. The core when raised projects into a sectional jacket, one portion of which is immovably mounted on the table, while 25 the other portion is hinged to swing open and has means for fastening it when closed. A split casing formed, preferably, of thin sheet metal is adapted to fit snugly within the jacket and surround the raised core. The 30 material of which the tile is to be formed is adapted to be tamped between the core and the casing, after which the core is withdrawn downward from the mold, the jacket opened, and the casing with the tile therein removed, 35 after which said casing is opened and removed from the molded object.

The invention also consists of certain other 40 novel features of construction and combinations of parts, which will be hereinafter more fully described, and pointed out in the claims.

In the accompanying drawings is shown the preferred form of the invention.

In said drawings, Figure 1 is a side elevation 45 of the table, portions thereof being broken away and showing the jacket open, the core of the mold being shown by dotted lines in lowered position. Fig. 2 is a plan view of a portion of a table and showing the 50 closed mold thereon, and Fig. 3 is a detail view of the casing with its ends disconnected.

Referring to the figures by characters of reference, 1 is a table-top supported by a suitable frame 2, in which is mounted a cross-strip 3, having a guide-opening 4 therein. A locking-lever 5 is fulcrumed at one end upon

one side of the frame and extends under the cross-strip and is supported near its other end upon a guide 6, secured to the frame 2. A link 7 is pivotally connected to one end of the frame and constitutes the fulcrum of a lever 8, which extends from the end of the frame and is pivoted at one end to a plunger 9, which is mounted to reciprocate within the opening 4. This plunger extends downward 65 from and is secured to or formed with a core 10, which is mounted to reciprocate within an opening 11, formed in the table-top. The core may be formed entirely of metal or may be of wood with a metal covering. 70

Arranged upon the table and surrounding the opening 11 is a jacket 12. This jacket consists of a section 13, which is immovably secured to the table, as by means of brackets 14, and a movable section 15 is hinged at one 75 edge to the fixed section 13 and is adapted to be closed thereagainst, so as to completely surround the opening 11. A catch or latch 16 is connected to the section 15 and is adapted to engage a keeper upon section 13, so as 80 to lock the jacket when closed. A casing 18, preferably formed of a sheet of thin metal, is adapted to fit snugly within the jacket 12, and the ends thereof overlap and are secured together in any preferred manner, as by 85 means of inwardly-extending lugs 19, formed at one end of the casing and adapted to be seated in slots 20, formed in the other end.

When it is desired to mold a tile by means of this machine, the jacket 12 is opened by 90 swinging the member or section 15 upon its hinges, and the core 10 is moved into position above the table by means of lever 8 and is locked in such position by swinging the lever 5 under the end of the operating-lever 8. 95 Casing 18 is placed around the core and its ends are locked together by means of lugs 19, after which the jacket is closed tightly about the casing and locked. The material of which the tile is to be formed is placed around 100 the core and within the casing and suitably tamped, after which the locking-lever 5 is pulled out of engagement with the operating-lever and the core drops by gravity out of the mold. The jacket is then opened and 105 the casing 18, with the molded object therein, is removed to a place where the tile may be dried, and the ends of the casing are then disengaged, and said casing will move from the molded object. The casing can then be 110 replaced in the mold and the above-described operation then repeated.

By using a machine such as herein described a tile can be quickly formed and then removed for drying without danger of being injured. Importance is attached to the particular means for fastening the ends of the casing together, because they permit said ends to be easily assembled and quickly detached without presenting any projections which will mar the appearance of the tile when finished. By mounting the operating-lever 8 on a link an absolutely vertical movement of the core is permitted.

The preferred form of the invention has been set forth in the foregoing description; but I do not limit myself thereto, as I am aware that modifications may be made therein without departing from the spirit or sacrificing the advantages thereof, and I therefore reserve the right to make such changes as fairly fall within the scope of the claims.

What is claimed is—

1. A molding-machine comprising a table, a core mounted to reciprocate therein, a jacket mounted upon the table and adapted to surround the core, said jacket consisting of movably-connected sections, one of said sections being immovably mounted upon the table, and a casing removably mounted within the jacket and comprising a single sheet

adapted to surround material within the jacket, the ends of said casing being adapted to overlap, and means upon said ends for holding them together when overlapping.

2. A molding-machine comprising a table, a core mounted to slide therein, a sectional jacket with one of its sections immovably secured upon the table, the other section being movably connected to the immovable section, a casing adapted to be seated within the jacket and formed of a single sheet adapted to surround material within the jacket, one end of said sheet having apertures therein, lugs integral with the other end and adapted to be seated within the apertures, a plunger movable with the core, a guide therefor, a link pivoted upon the table, a lever fulcrumed upon and movable with the link, one end of said lever being pivoted to the plunger, and a locking-lever mounted to swing into the path of the first-mentioned lever when the core is raised.

In testimony that I claim the foregoing as my own I have hereto affixed my signature in the presence of two witnesses.

DAVID LEONARD.
